UNITED STATES PATENT OFFICE.

JOHN E. FOWLER, OF OLEAN, NEW YORK.

WINDOW FIXTURE.

Application filed October 13, 1923. Serial No. 668,413.

To all whom it may concern:

Be it known that I, JOHN E. FOWLER, a citizen of the United States, and resident of Olean, in the county of Cattaraugus and 5 State of New York, have invented certain new and useful Improvements in Window Fixtures, of which the following is a specification.

The present invention relates to window fixtures and more particularly to the type 10 designed to be clamped to a window casing to sustain shades or curtains or both. An object of the invention is to provide a construction which will be inconspicuous, simple 15 in operation, inexpensive to manufacture and durable in use.

To these and other ends, the invention 20 consists of certain parts and combinations of parts, all of which will be hereinafter described, the novel features being pointed out in the appended claims.

In the drawings:

Fig. 1 is a top view of the fixture showing the latter clamped to a window casing; 25 Fig. 2 is a front view;

Fig. 3 is an enlarged view showing the adjustable connection between the two bars;

Fig. 4 is a section on the line 4—4, Fig. 3;

Fig. 5 is a section on the line 5—5, Fig. 3; 30 Fig. 6 is an enlarged section on the line 6—6, Fig. 2; and

Fig. 7 is a section on the line 7—7, Fig. 2.

Referring more particularly to the drawings, 1 indicates the window casing and 2 and 3 indicate two bars formed, in this instance, from sheet metal and each having at its outer end a rearwardly extending hook 4 which has an inwardly extending penetrating projection 5.

Connecting the two bars 2 and 3 is a link 6 which preferably has a fixed pivotal connection at 7 with a bar 2 and adjustable pivotal connection in the form of a removable screw 8 with the bar 3, the adjustment 45 being secured, in this instance, by providing the bar 3 with a longitudinal series of openings 9 through any one of which the pivot screw 8 may pass. The link 6 lies between the overlapping ends of the bars 2 and 3 and, when in one position, as shown in dotted lines in Fig. 3, has the bar shifted relatively to each other in such a manner that the hooks 5 will be freed from the window casing, whereas when the link is shifted 50 to the full line position shown in Fig. 3, the relation between the bars is such that the

hooks 5 will penetrate the window casing. The adjustable connection between the link and the casing is provided in order that casings of different widths may be engaged. 60

The interlocking connection is secured by providing the link with a resilient arm 6^a having at its outer end a forwardly projecting lug 6^b and on opposite sides of the resilient arm, two rearwardly projected lugs 6^c for engaging with opposite sides of the bar 2. When the fixture is clamped to a window casing, the lugs are held by the resiliency of the arm 6^a on opposite sides of the bar 2 and in order to release the 70 fixture from the window casing the arm 6^a is flexed to bring the projections 6^c out of engagement with the bar 2 after which the arm with the link may be swung to the 75 dotted line positions.

The fixture may be employed for securing window curtains and to this end there has been secured near the opposite outer ends of the bars 2 and 3 curtain sustaining means such as brackets 10 in the form of L shaped 80 members, each having one arm projected forwardly from one of the bars 2 or 3 and the other arm extending laterally parallel with the bar 2 or 3 toward the other bracket so that a curtain sustaining tube 10^a may 85 connect said laterally extending arms.

The fixture may also be employed for sustaining a shade and to this end shade sustaining means such as shade brackets 11 are provided each of which may be adjustably 90 secured to one of the bars 2 or 3, this, in this instance, being obtained by providing each bracket 11 with an arm 12 formed with longitudinal slots 13. Through these slots headed securing devices 14 extend being 95 anchored in the arm on which the bracket 11 is mounted.

It is apparent that this construction may be readily fitted to a window casing to firmly support curtains or shades or both. 100 The two bars are so connected that hooks at opposite ends thereof may be drawn in firm engagement with the edges of the window casing. The connecting means is in the form of a link which interlocks with one of the members to sustain the parts in their adjusted positions. The link also has an adjustable connection with one of the members so that casings of different sizes may be engaged. The curtain sustaining means enables the ready mounting or dismounting 105 of the curtain due to the fact that the tube 110

which connects the L shaped members will become disconnected from such members when the bars are adjusted to remove the fixture from the window casing. The structure, as a whole, is durable, inexpensive to manufacture, simple in operation and is inconspicuous upon the window casing.

What I claim as my invention and desire to secure by Letters Patent is:

10. A window fixture comprising a sustaining device for a shade or the like, two bars to each of which a sustaining device is secured, a rearwardly extending hook near the

outer end of each bar, a resilient link pivoted on the front face of one bar near the inner end of the latter and having at its other end two rearwardly projecting lugs for engaging the opposite edges of said bar, and a headed pivot eccentrically arranged on the front face of said link, the other bar having its inner end lying in front of the link and provided with a longitudinally extending series of openings in any one of which the headed pivot may lie.

JOHN E. FOWLER.
